UNITED STATES PATENT OFFICE.

JOHN M. ROHLFING, OF PLAINFIELD, NEW JERSEY, ASSIGNOR TO AMERICAN CAR AND FOUNDRY COMPANY, OF NEW YORK, N. Y., A CORPORATION OF NEW JERSEY.

BRAKE FOR ELEVATORS.

Original application filed December 15, 1923, Serial No. 680,880. Divided and this application filed January 11, 1926. Serial No. 80,534.

In the drawings:

Fig. 1 is a broken partial view in elevation of an elevator equipped with a braking means constructed in accordance with this invention;

Fig. 2 is a partial view in side elevation of the structure shown in Fig. 1, parts being broken away to show the braking means;

Fig. 3 is a view in front elevation of the structure shown in Fig. 2, part of the guide being broken away to show the braking means in elevation;

Fig. 4 is a horizontal section taken on the line 4—4 of Fig. 1, and

Fig. 5 is a vertical section taken on the line 5—5 of Fig. 3.

This invention relates to braking means for elevators and it is an object of this invention to provide a braking means which will be operated to check the descent of the elevator immediately the elevator begins to accelerate at too rapid a rate, whether the excessive acceleration be due to the breaking of the supporting cables or to an excessive speed of the operating motors. It is also an object of this invention to provide a braking means of the type described which will be immediately operative upon the commencement of the excessive speed of descent, irrespective of whether the elevator is stopped or moving at the instant the excessive speed commences.

In the drawings the invention is shown in connection with the elevator shown in my prior application, Serial No. 680,880 filed Dec. 15, 1923, of which application this application is a division. This elevator comprises a frame having vertical I-beam side members or guides 1 mounted upon a wheeled truck (not shown) and having their upper ends connected together by channels 2. At the upper ends of the guides or guideways 1 are secured brackets 4 which support guide rollers 6 engaging a guide member 8 which is supported in any desired manner so as to permit free movement of the frame longitudinally of the guide member 8. Carried by the channels 2 is a bracket 10 on which are mounted, but insulated therefrom, collector brushes 12 which collect current from conductors (not shown) strung along the guide member 8 to furnish a source of current for the operating motors of the elevator.

Mounted for reciprocation in the guides 1

is a frame only the upper portion of which 55 is shown and which comprises vertical members consisting of plates 14 having angles 15 secured thereto, the angles being secured so as to present outwardly projecting flanges 16. (Fig. 4). The plates 14 are connected at 60 their tops by spaced channels 18 secured thereto by angles 20. (Figs. 3 and 4). Mounted on the channels 18 are brackets 22 in which is secured a hoisting or operating means comprising a motor 24 which operates 65 a winding drum 26. About the drum 26 are wound the cables 28 which pass over sheaves 30 mounted in a bracket 32 carried by the channels 2 and having their ends secured to the winding drum 26 and to the casing surrounding the winding drum 26.

To guide the elevator in its movements along the upright structures or guides 1, the elevator is provided with guide means embracing said guides 1, including rollers 36 75 mounted in brackets 38 secured to the outwardly projecting flanges 16 of the angles 15. These rollers 36 project through openings in these flanges 16 and engage with the outer sides of the inwardly projecting juxtaposed flanges 39 of the I-beam guides 1. Similar rollers 40 are mounted in brackets 42 secured to the plates 14 and project through openings in the plates 14 and engage with the edges of the inner flanges 39 85 of the guides 1.

Mounted on the elevator channels 18 are brackets 44 secured to the channels by bolts 46 which pass through openings in the brackets 44 and in plates 48 which contact 90 with the bottom flanges of the channels 18 (Fig. 4). Each of the elevator brackets 44 has a downwardly tapered wedge portion 50 (Fig. 5) which projects into the space between the inwardly projecting flanges 39 95 of the corresponding guide 1, this taper of the portion 50 providing inclined surfaces 52 which are engaged by correspondingly inclined surfaces on tapered brake shoes 54 placed between the surfaces 52 and the 100 flanges 39. When expansively actuated by the wedge 50 between them, the pair of brake shoes 54 act between and against the opposed internal surfaces of the guide flanges 39. The brake shoes 54 are provided with 105 hook-shaped portions 56 at their upper ends which engage lugs 58 formed integral with the tapered portions 50. The tapered por-

tions 50 are also provided with cylindrical chambers 60 which are open at their lower ends and communicate with threaded openings at their upper ends which lead to the 5 upper surfaces of the portions 50 and in which are threaded tubes 62 through which pass rods 64. The rods 64 are provided with squared ends 66 which secure thereon followers 68 having cylindrical portions 70 10 which slidably engage in the chambers 60 and serve to guide the followers 68. The followers 68 are formed with inclined surfaces 72 which engage with correspondingly inclined surfaces on the brake shoes 54. 15 Mounted on the rods 64 in the chambers 60 are coil springs 74 which are confined between the followers 68 and followers 76 that engage either the upper ends of the chambers 60 or the lower ends of the tubes 62. 20 In other words, the springs 74 act between the bracket wedges 50 and the upward counterweight connections so as to normally keep the brake shoes out of action. The rods 64 are threaded at their upper ends and have 25 mounted thereon collars 78 and lock nuts 80 which serve to adjust the normal compression of the springs 74. Secured to the rods 64 are eyes 82 to which are fastened ends of cables 84 which pass over sheaves 30 86 pivotally mounted adjacent the upper ends of the guides 1, the other ends of the cables 84 being secured to the counterweights 88 which travel in grooves formed by the outwardly projecting flanges 89 of 35 the guides 1 and angles 90 which are secured to the flanges 89 and have inwardly projecting flanges 92. The counter-weights 88 are formed with projecting portions which engage in back of the flanges 92. At their 40 lower ends the flanges 92 are connected by cross pieces 94 which serve as stops to limit the downward movement of the counterweights 88.

In operation the compression of the springs 45 74 is adjusted so that under normal conditions of operation the springs will effect the starting of the counter-weights 88 without further compression of the springs, the design of the parts being such that under this condition 50 the brake shoes 54 do not bind against the inwardly projecting portion 50 of the brackets 44 and the flanges 39 of the guides 1, thus permitting the elevator free movement in both directions. Should the hoisting cables 55 28 break while the elevator is in an elevated position or should the motor be operated so as to cause the elevator to drop and accelerate at a rate in excess of the desired rate, the pull due to the inertia of the counterweights 88 will be greater than that for which the springs 74 are adjusted, and the rods 74 and associated parts will be drawn upward, so that a further compression 60 of the springs 74 will take place. As the 65 springs 74 are compressed further in re-

sponse to the elevator acceleration and the consequent counterweight pull, the followers 68 are actuated by the rods 64 and shift or force the brake shoes 54 upward between the wedge portions 50 and the flanges 39 of the 70 guides 1, thereby wedging the brake shoes between the members 50 and the guides 1 and forcing or expanding them against the latter, thus exerting a braking action upon the elevator, the downward movement of the 75 elevator tending to increase the braking action of the shoes as thus actuated. After the brakes have been applied either by the breaking of the cables 28 or by excessive speed due to the operation of the motor 24, the operation of the motor to raise the elevator will raise the brackets 44 and the tapered portions 50 between the brake shoes 54 and destroy the braking action of the shoes so that after the braking action has taken place it is merely necessary to operate the elevator in a direction to raise it in order to release the brake shoes from their wedging engagement with the guides 1 and the tapered portions 50 on the brackets 44. 80 85 90

What is claimed is:

1. An elevator braking mechanism comprising weight retracted oppositely and laterally movable wedge elements to engage opposed walls of an elevator guide, a head disposed below the wedge elements and raised vertically against the latter to cause them to engage the elevator guide incident to unsafe acceleration of the elevator. 95
2. In an elevator safety attachment, co-acting slidably connected wedge elements carried by the elevator and movable in one of the guides therefor, and normally held out of contact of such guide, but moved into gripping contact with the guide by the sliding wedge action of the wedge elements when the elevator travels at an unsafe velocity. 100
3. In combination, an elevator, co-acting slidably connected wedge elements attached to opposite sides of the elevator, and operable to frictionally engage parts of the elevator shaft to brake the movement of the elevator when the latter travels at an unsafe rate of speed. 105
4. An elevator braking mechanism comprising an upright structure with opposed internal surfaces, brake shoes between said surfaces, and expanding means between the brake shoes for forcing them apart against the surfaces, in response to acceleration of the elevator. 110
5. An elevator braking mechanism comprising an upright structure with opposed internal surfaces, brake shoes between said surfaces, a down-tapered expanding wedge between said brake shoes, and means responsive to acceleration of the elevator for raising said brake shoes and thus causing their expansion against the surfaces by the wedge. 115
6. An elevator braking mechanism com- 120 125 130

prising a guideway with opposed internal surfaces, guide means for the elevator externally embracing said guideway, and brake means carried by the elevator for acting between said opposed surfaces.

7. An elevator braking mechanism comprising a guide member with juxtaposed flanges, guide means for the elevator engaging said flanges, and brake means carried by the elevator for acting between the flanges.

8. An elevator braking device comprising an elevator bracket, brake shoes and actuating means therefor carried by said bracket, an upward extending counterweight connection from said actuating means, and a spring acting between said connection and said bracket for normally keeping the brake shoes out of action.

9. An elevator braking device for acting between opposed surfaces, comprising brake shoes for engaging the surfaces, a down-tapered expanding wedge between said brake shoes, means for drawing said brake shoes upward to cause their expansion by the wedge including an upward extending counter weight connection, and an adjustable spring mounted on said wedge for normally keeping the brake shoes out of action.

10. In a device of the class described, an elevator, guides for said elevator, supporting brackets for said elevator, counter-weights, flexible means connected to said counter-weights, followers connected to said flexible means, springs interposed between said followers and brackets, and braking means for said elevator operated by said followers upon the yielding of said springs.

11. In a device of the class described, an elevator, guides for said elevator, supporting

brackets for said elevator having surfaces inclined to said guides, counterweights, flexible means connected to said counter-weights and having connections through said brackets, followers carried by said connections, springs interposed between said followers and brackets, and brake shoes shiftable by said followers into wedging engagement with said inclined surfaces and guides upon the yielding of said springs.

12. An elevator safety catch, including a plurality of interfitting members, one of which being arranged to be rigidly attached to part of an elevator, and having longitudinal slidable engagement with the others, and means operable by the acceleration of the elevator to expand such interfitting elements into frictional engagement with a stationary object arranged along the path of movement of the elevator.

13. An elevator safety catch, including a wedge element to be rigidly attached to one side of an elevator and movable vertically in the guide thereof, brake shoes upon opposite sides of the wedge element, and having wedge surfaces co-incident to the wedge surfaces of the wedge element and normally arranged out of contact with the guide, a head slidably associated with the wedge element and upon which the brake shoes rest, and means operable for the unsafe acceleration of the elevator for raising the head and thereby shift the brake shoes along the wedge element to cause the latter to expand against the guide.

In witness whereof I have hereunto set my hand.

JOHN M. ROHLFING.
